US00D531658S

(12) United States Design Patent (10) Patent No.: US D531,658 S
(45) Date of Patent:  *Nov. 7, 2006

(54) TYPE FONT

(75) Inventors: Steve Matteson, Holland, MI (US);
Carl Crossgrove, San Francisco, CA
(US)

(73) Assignee: Microsoft Corporation, Redmond, WA
(US)

(*) Notice: This patent is subject to a terminal disclaimer.

() Term: 14 Years

(21) Appl. No.: 29/196,450

(22) Filed: Dec. 31, 2003

(51) LOC (8) Cl. 18-03

(52) U.S. Cl. D18/24

(58) Field of Classification Search D18/24-28,
D18/30, 32; 101/398, 399; 434/159, 160,
434/161-165

See application file for complete search history.
